UNITED STATES PATENT OFFICE.

CYRIL W. LE NOUE, OF LOS ANGELES, CALIFORNIA.

LOCK.

Application filed July 28, 1927. Serial No. 209,057.

This invention relates to locks and pertains more particularly to a lock of the tumbler type adapted to be used for the locking of the operating mechanism of a vending machine and whereby a specially designed slug key, which takes the place of the ordinary coin now commonly used for this purpose, is utilized for the unlocking of the operating mechanism and after said mechanism has been operated the slug key drops from the lock and is deposited into a receptacle to which only the proprietor of the machine has access.

The object of the invention is to provide a lock of the character above recited which will be highly efficient in operation, simple and durable of structure and which will be difficult of manipulation by any person other than one in possession of the requisite key slug.

The above recited and other objects of the invention will be more fully described in the following specification and will be exemplified in the accompanying drawings, in which:

Figure 1 is a front view of a casing embodying the invention parts being broken away and shown in section in order to more fully disclose the working parts.

Figure 2 is an irregular section taken approximately on the line 2-2 of Figure 1 viewed in the direction indicated by the arrows.

Figure 3 is a section taken on the line 3-3 of Figure 1 viewed in the direction indicated by the arrows.

Figure 4 is a section taken on the line 4-4 of Figure 1, viewed in the direction indicated by the arrows.

Figure 5 is an enlarged section taken on the line 5-5 of Figure 1, viewed in the direction indicated by the arrows.

Figure 6 is a section taken on the line 6-6 of Figure 5, viewed in the direction indicated by the arrows.

Figure 7 is a view of a fragment of the back of the casing showing the lever for operating the mechanism of the vending or other machine.

Figure 8 is a side view of a key slug adapted to be used for unlocking the lock.

Figure 9 is a section taken through the same on the line 9-9 of Figure 8.

In carrying out the invention a casing 10 is provided which may either be a separate unit or form a part of the wall of a vend-

ing machine (not shown) in which the mechanism to be operated by the lock is enclosed.

The casing 10 comprises a front plate 11 and a back plate 12 which are secured together by means of the centrally disposed screw 13 and other screw 14. The plate 11 has formed in it an annular chamber 15, and the plate 12 is provided with an annular centrally disposed boss 16 which projects into the chamber 15 and also with an annular flange 17 at its periphery which also projects into the chamber 15, thus forming an annular groove 18 in which is mounted for rotation a ring 19.

Mounted for rotation in chamber 15 is an annular disc 20 which is disposed between the inner surface of plate 11 and the inner surfaces of the boss 16 and flange 17.

A pin 21 is secured to the ring 19 and projects through a segmental slot 22 in the back plate 12 and has pivoted to it a link 23 adapted to form a connection with the slot machine mechanism (not shown) to operate the same to perform any desired function.

An operating handle 24 is secured to the disc 20 and projects through a segmental slot 25 formed in plate 11, which also has formed in it, a slot 26 for the admission of a slug key 27. Formed in the back plate 12 is a slot 28 through which the key slug 27 is ejected.

The ring 19 is made up of several pieces, for the purpose of conveniently machining the same, suitably secured together to form an annular pocket 29 therein, the opposite side walls of which are provided respectively with annular ribs 30 and annular grooves 31 to correspond with ribs and depressions 31' indicated at 31' on the key slug 27, and an annular slot 32 which communicates with the pocket 29 and in which an annular rib 33 secured to the disc 20 projects, and said rib is provided on its inwardly projecting surface with a notch 34 to receive the key slug 27, said slug being placed between the edges 35 and 36 of the notch.

The ring 19 is provided with an aperture 37 in its front wall adapted to register with the aperture 26 when the mechanism is in its initial or starting position in order that the key slug 27 may be inserted into the ring.

Mounted in the casing 10 are three groups of radially disposed spring pressed plungers 38, 39, and 40, the plungers of groups 38 and 39 pointing inwardly and the plung-

ers of group 40 pointing outwardly as shown in Figure 1 of the drawings.

Plunger group 38 comprises the individual plungers 41, 42 and 43, the plunger 41 being of a certain diameter, the plunger 42 of a larger diameter and plunger 43 of a still larger diameter and said plungers are mounted to reciprocate in corresponding sockets in the casing 10 and are pressed inwardly by means of springs 44.

Disposed in front of the plungers are tumblers 45, 46, and 47 of corresponding diameters which at certain intervals during the operation of the lock are disposed in sockets indicated at 48 and 49 formed in ring 19.

The key slug 27 is provided on its outer edge with indents 50 and cam surfaces 51 and on its inner edge with indents 52 and cam surfaces 53.

20 Mounted in sockets formed in the ring 19 similar to those indicated at 48 and 49 and disposed forward of tumbler 47 is a pusher tumbler 54 of greater diameter than tumbler 47, adapted to ride along the inner peripheral surface of the annular groove 18.

Plunger group 39 comprises the individual spring pressed pistons 55, 56, 57 and 58 mounted in suitable bores formed in the casing 10 said bores communicating with bores 59, 60, 61, 62 which are of increasing diameters and are adapted to receive the respective tumblers 45, 46, 47 and 54 during a transferring operation.

Plunger group 40 comprises the individual 35 plungers 63 and 64 and corresponding tumblers adapted to engage with the concaved edge of the key plug 27 and to operate in identically the same manner as plungers of group 38.

40 Another group of spring pressed pistons indicated at 65 adapted to press outwardly but in other respects constructed similar to the group 39 is provided, and the bores in the casing 10 operating with the group are 45 adapted to receive the tumblers of group 40. The mechanism constituting groups 40 and 65 could be dispensed with as they merely serve to form a certain combination and it is obvious that the arrangement of all of the 50 tumblers may be varied to form a different combination.

When the mechanism is in its initial position, the aperture 37 in ring 19 is in register with the aperture 26 in casing 10 and the 55 notch 34 is also in register with these apertures and the plungers of groups 38 and 40 are pressed into the sockets indicated at 48 and 49 thus locking the ring 19 to the casing 10. When the handle 24 is moved in the 60 direction indicated by the arrow A, the key slug is pushed forward by the edge 35 of slot 34 to assume a position shown in Figure 1 of the drawings. During this operation the various plungers are pushed into their sockets by the cam surfaces 51 and 53 on the key 65

slug and the tumblers then drop into position into the indents 50 and 52 in the key, and the push tumbler 54 is engaged by the forward cam surface.

Upon continued movement of the handle 70 the various tumblers, the ring and key are carried around until the ring 19 is stopped by reason of the pin 21 engaging with the edge of slot 22. At this time the various tumblers are in register with the corresponding bores in groups 39 and 65 and consequently upon a continued movement of the handle the cam surfaces on the key slug act to push the tumblers into these bores. Continued movement of the handle pushes the 80 key into register with the slot 28 through which it drops by force of gravity, the casing being disposed on a slant to facilitate this action.

As the key passes from engagement with 85 the tumblers they are forced into their various sockets in the ring, whereupon the ring carrying the tumblers will be returned to its initial position by means of the spring 66 which is secured to the lever 21 and casing 10. The handle may be then moved back to its initial position and the above described action repeated upon the insertion of another properly calibrated key.

Having thus described my invention what 90 I claim is:

1. A lock comprising a casing provided 100 with key slug inlet and discharge openings; a manually operable oscillating member mounted in said casing; a second oscillating member mounted in said casing provided with a socket, key slug engageable means to turn said second oscillatory member; a spring pressed plunger mounted in said casing 105 adapted to engage in said socket; a tumbler adapted to engage in said socket and to be operated by said plunger; a spring pressed piston mounted in said casing and arranged in advance of said plunger, said casing being provided with a socket disposed forward of said piston adapted to receive said tumbler; and a key slug adapted to be 110 engaged by said manually operable member and to operate said plunger and tumbler whereby said plunger will be disengaged from said second oscillating member and said tumbler will be carried forward with said key slug and second oscillating member and become deposited in the socket disposed forward of said piston.

2. A lock comprising a casing provided 115 with key slug inlet and outlet openings; a disc mounted for oscillation in said casing provided with key slug engaging means; a 120 ring mounted for oscillation in said casing provided with a plurality of sockets of various diameters; a plurality of spring pressed plungers of various diameters; mounted in said casing adapted to engage in the sockets in said ring; a plurality of tum- 125

blers adapted to reciprocate in the sockets in said ring and to be engaged by said plungers; a push tumbler adapted to reciprocate in one of said sockets; a plurality of spring pressed pistons mounted in said casing and arranged in advance of said plungers and behind a plurality of sockets of various diameters formed in said casing; and a key

slug adapted to be engaged by said disc and to engage with said tumblers to move said ring and the tumblers into alignment with the sockets in said casing and to force them therein against the pressure of said pistons. 10

In testimony whereof I hereunto affix my signature.

CYRIL W. LE NOUE.
